132,744

DESIGN FOR AN ILLUMINATING PROJECTOR

William F. Peck, Snyder and John T. Armbruster,
Niagara Falls, N. Y., assignors to Spencer Lens
Company, Buffalo, N. Y., a corporation of New
York

Application March 5, 1942, Serial No. 106,084

Term of patent 14 years

To all whom it may concern:

Be it known that we, William F. Peck and John T. Armbruster, citizens of the United States, residing at Snyder and Niagara Falls, respectively, in the counties of Erie and Niagara, respectively, and State of New York, have invented a new, original, and ornamental Design for an Illuminating Projector, of which the following is a specification, reference being made to the accompanying drawing, forming a part thereof.

Fig. 1 is a perspective view of an illuminating projector, showing our new design.

Fig. 2 is a front elevational view thereof; and Fig. 3 is a side elevational view thereof.

The essential features of our design are shown in full lines in the drawing.

We claim:

The ornamental design for an illuminating projector, substantially as shown and described.

JOHN T. ARMBRUSTER.

WILLIAM F. PECK.
